UNITED STATES PATENT OFFICE.

CHARLES C. HUGHES AND ROLAND O. BETTERLY, OF PHILADELPHIA, PENNSYLVANIA.

ENGINE VALVE AND CASING.

Application filed February 7, 1922. Serial No. 534,753.

To all whom it may concern:

Be it known that we, CHARLES C. HUGHES and ROLAND O. BETTERLY, citizens of the United States, residing at Philadelphia, in 5 the county of Philadelphia, State of Pennsylvania, have invented certain new and useful Improvements in Engine Valves and Casings; and we do hereby declare the following to be a full, clear, and exact description of the invention, such as will enable others skilled in the art to which it appertains to make and use the same.

This invention relates to new and useful improvements in explosive engines and 15 particularly to valves therefor.

One object of the invention is to provide a valve of the rotary type which is so constructed and arranged that the upper and lower faces, as well as the peripheral face, 20 may be easily lubricated.

Another object of the invention is to provide a valve of the rotary type which is mounted within the head of the engine cylinder in such a manner that only a small 25 portion, equal to the size of the port thereof, is subjected to contact of the exploding gases.

Another object is to provide a valve of this character which may be easily and 30 quickly removed from the head of the cylinder without dismantling the engine or removing the head.

Other objects and advantages will be apparent from the following description when 35 taken in connection with the accompanying drawing.

In the drawing,

Figure 1 is a top plan view of a portion of an engine made in accordance with the 40 invention and partly in section.

Figure 2 is a vertical sectional detailed view on the line 2-2 of Figure 1.

Figure 3 is a perspective view of the valve removed from the engine.

Referring particularly to the accompanying drawings 45 represents the engine cylinder which has the explosion chamber 11, and the water jacket 12, the upper end of the cylinder being open as shown at 13.

Mounted on the open end of the cylinder 50 is the head 14 having in the center of its lower end an upwardly arched recess 15, which serves to close the said opening of the cylinder, a suitable packing 16 being disposed between the cylinder and the head.

This head is provided with the water jacket

17 and has a port 18 in one side leading into the head. In the lower portion of the head is a vertical passage 19 which extends at right angles to the port 18. Formed in the interior of the head 14, and depending downwardly thereinto, is a cage 14', the same having openings 20 which communicate with the surrounding water jacket 17. This cage has its upper end open to receive 60 the casing 21 which has the central hollow stem 22 surrounded by the water jacket 23, said casing having openings 24 registering with the openings 20, whereby a free movement of water through the head and casing 65 is permitted.

The upper end of the casing has a laterally extending flange 25, which is secured to the upper end of the head by the bolts 25'. Formed in one side of the lower portion of 75 the casing is a curved passage 26, the opposite ends of which communicate with the ports 18-19. Rotatably mounted between the bottom walls of the cage 14' and the casing 21 is the rotary valve 27, said valve 80 having a port 28 adapted to register with the port 19 and the passage 26, to permit the egress of the burnt gases. This valve is formed with a stem 29, which extends upwardly through the stem 22 above the 85 head 14 and within the upper extension 22' of the stem 22. The upper end of the stem 29 is slightly reduced at 30 and has secured thereon a gear 31, which meshes with a gear 32, carried on a shaft 33, and which 90 shaft is supported on a bracket 34, on the head 14. A packing 35 composed of a plurality of thin sheets of soft metal, such as brass, is disposed between the head and flange 25, as clearly seen in the sectional 95 view of Figure 2.

Also formed through the side of the head 14 is a port 18', which leads into a curved passage 26', said passage 26' communicating with the vertical passage 19' 100 leading into the end of the cylinder.

As the valve 27 rotates the port 28 registers successively with the passages 18-19 and 18'-19', so that the burnt gas will be permitted to exhaust from the cylinder in 105 the first instance and the live gases permitted to enter the cylinder in the second instance.

It will be understood that the mechanism described is duplicated for each cylinder 110 of the engine, and that the shaft 33 has a gear 32 for each gear 31. It will of course

be understood that the valves are so arranged that the intake and exhausts of the different cylinders will be in proper succession.

Particular attention is called to the cage 14' and the casing 21, the latter of which supports the valve 27 and its stem 29, such construction permitting quick and easy removal of the valve from the head 10 of the cylinder without any other removal of engine parts. It will be noted that when the brackets 34 together with the shaft 33 and its gears 32, are removed, the casing 21, together with the valve 27, stem 15 29, and gear 31, may be bodily lifted from the cage 14' after the bolts 25' have been removed.

Formed longitudinally and centrally through the stem 29 is an oil channel 36, 20 which leads down to the disk 27 where a horizontal radial branch 37 extends to the periphery of the disk. From the branch 37 extends the vertical branches 38, leading respectively to the upper and lower faces 25 of the disk. In the faces of the cage and casings with which the upper and lower faces engage, there are formed the oil passages 39—40 respectively.

It will be noted that between the lower 30 wall of the cage 14' and the bottom wall of the heads 14, there is formed a space 41 in which water passes so that the heat from the cylinder will not come in direct contact with the casing or valve.

It will be noted also that the only point 35 on the valve 27 which comes into direct contact with the exploding gases is that portion of the valve 27 which passes over the ports 19 and 19'; the remainder of the 40 valve 27 being protected by the water jacketed lower wall of the cage 14' against any and all pressure and heat from within the engine cylinder.

It will be noted that the upper and lower 45 faces of the valve 27 converge toward the

periphery of the body of the valve, whereby to permit of greater resistance to distortion; to assist in equalizing the wear of the valve; to increase the area of the bearing surface, and to aid in the proper and 50 efficient lubrication of the valve.

What is claimed is:

1. The combination with an engine cylinder, having a removable head at the top, a depending cage supported in the head, 55 a removable casing in the cage and having a water jacket therearound, the casing and cage having inlet and exhaust ports and a valve movable in the casing and having ports registering intermittently with the 60 ports of the casing and cage.

2. The combination with an engine cylinder having a head provided with laterally and downwardly directed ports, a depending cage supported in the head and 65 having communication with the ports, a casing removably supported in the cage and having a communication with the ports, and a rotatable valve in the casing having vertical ports therethrough, said valve including a vertical stem operable from without the head.

3. The combination with an engine cylinder having a head formed with ports, a removable cage in the head having passages 75 registering with and forming parts of said ports, and a rotary valve mounted in the head out of contact with the exploding gases in the cylinder, except for an area 80 equal to the area of said ports and provided with ports registrable with the ports of the head.

In testimony whereof, we affix our signatures, in the presence of two witnesses:

CHARLES C. HUGHES.
ROLAND O. BETTERLY.

Witnesses:

CHAS. R. HUGHES,
WALTER K. Wood.
